UNITED STATES PATENT OFFICE.

JOHN S. LYON, OF ROCHESTER, NEW YORK, ASSIGNOR OF ONE-HALF TO JOHN BARTHOLOMEW, OF ROCHESTER, NEW YORK.

COMPACT POWDER HOLDER.

Application filed January 11, 1926. Serial No. 80,514.

My present invention relates to toilet requisites and more particularly to containers or holders for face powder. Such powder is now largely sold in compressed cakes contained in suitable boxes and supported therein in a metallic holder that prevents it from cracking or chipping and at the same time constitutes a re-fill for the box or vanity case when desired. Such a holder 5 is shown in my pending application Serial Number 634,662, filed April 26, 1923 and the present invention is an improvement on the construction therein shown whereby the holder is made light, strong and unyielding 10 but is additionally provided with means for locking the powder cake therein. To these and other ends the invention resides in certain improvements and combinations of parts all as will be hereinafter more fully 15 described, the novel features being pointed out in the claim at the end of the specification.

In the drawings:

Figure 1 is a central section through a 25 powder box containing a cake and holder constructed in accordance with and illustrating one embodiment of my invention.

Figure 2 is an enlarged vertical section through the powder holder and cake; 30 Figure 3 is a bottom view of the powder holder, and

Figure 4 is a top view thereof before it is filled.

Similar reference numerals throughout 35 the several views indicate the same parts.

Referring first to Figure 1, 1 indicates the body and 2, the lid of a common form of powder box having a cylindrical lining wall 3 over which the flanges of the lid 40 engage. Within the box is a dome shaped powder cake 4 within a metallic holder indicated generally at 5.

The holder consists of a shallow dish or 45 tray embodying a bottom 6 and a flanged rim 7 and as before stated, this must be light in weight so that it is stamped from thin sheet metal. The powder is compacted into the holder under pressure by suitable filling machinery in an effort to cause it

to cling so intimately to the surfaces of the 50 holder that it will adhere thereto. However, a difficulty has been experienced in that the pressure exerted on the holder in filling tends to cause the side walls or flange 7 to 55 spring or give outwardly under the lateral pressure of the powder. This, in turn, causes the bottom 6 to bulge upwardly so that while the cake 4 is in actual process of being molded it is molded to a tray or 60 holder that is in distorted condition. Thus 65 when the pressure is relieved the slightly convex bottom 6 to which the cake has been shaped recedes to a normal flat condition and draws away from an intimate supporting contact with the powder making loosening and breakage probable if not inevitable. 70

My prior application above identified, discloses means for correcting these difficulties in a very simple manner. An annular groove 8 is punched in the bottom 6 of the 75 holder closely adjacent to the flange or side wall 7 which forms a corresponding annular rib on the inside of the holder. The crimping of the metal has the well known effect of hardening the metal so that it is 80 less flexible and gives less of a tendency for the wall 7 to spread. It also strengthens the bottom of the holder in the region where the relative movement of the flange and bottom occurs.

In the practice of the present invention I employ this invention of my prior application but also provide additional means for adding rigidity to the holder and at the same time locking the powder cake 4 in 85 place. This consists of an inwardly turned flange 8 on the side wall 7 that projects downwardly at an angle as clearly shown in Figure 2. When the powder cake 4 is pressed into place, it flows under this flange 90 and into locking engagement therewith. Aside from this locking function, the formation of this flange gives a smooth and rounded edge to the holder that is pleasing to the touch and also gives additional surface for the engagement of locking devices 95 that may be used to retain the holder in a special receptacle.

I claim as my invention:

A tray or holder for compacted powder cakes of the character described embodying a sheet metal bottom having a surrounding shallow side wall, the upper edge of the material forming said wall being flanged inwardly and downwardly so that its margin

is crimped against the inner face of the side wall at an outwardly spreading incline to strengthen the holder, a continuation of the outer surface of the side wall thus becoming an inner wedging surface for the cake.

JOHN S. LYON.
